CONCRETE CONSTRUCTION

Ralph D. Yankee, Kansas City, Mo.

Application October 24, 1941, Serial No. 416,355

7 Claims.

(CL 72—30)

This invention relates to concrete construction particularly suitable for foundations, walls, beams, columns, pilasters or other reinforced structures, and has for its principal object to provide a precast unit type construction which facilitates erection and reduces cost of concrete structures.

Other objects of the invention are to provide precast units which are readily assembled to form a hollow wall structure that may be filled with insulation or used as a form in pouring a concrete core when solid walls are required; to provide a unit construction that is water-tight and completely weather-proof; to provide a reinforced concrete construction that is not affected by weather conditions in that the precast units shut off air, heat, and sun effects from the concrete core while setting; and to provide a construction which results in an outer wall surface of uniform appearance and free of defects such as honeycomb, rust streaks from the reinforcement, and form marks.

A further object of the invention is to provide inner and outer units that may comprise an entire bay or side wall of a building and which units may have the reinforcement, ties, tie rods, dowels, and dowel sockets set in place and the concrete poured while in flat position and then raised to erect position in the wall.

In accomplishing these and other objects of the invention, I have provided improved details of structure, the preferred forms of which are illustrated in the accompanying drawings, wherein:

Fig. 1 is a perspective view of a corner of a building constructed of precast units in accordance with the present invention, parts being broken away to better illustrate the construction.

Fig. 2 is a vertical section through one of the walls on the line 2—2 of Fig. 1.

Fig. 3 is a vertical section through a window opening in the wall and taken on the line 3—3 of Fig. 1.

Fig. 4 is a fragmentary perspective view of one of the precast units, particularly illustrating the reinforcement and dowels whereby the units are connected together.

Fig. 5 is a horizontal section on the line 5—5 of Fig. 1.

Fig. 6 is a modified form of the invention wherein the inner and outer units are used as a form in pouring a concrete core in forming a solid wall construction.

Fig. 7 is a perspective view of one of the units employed in the structure illustrated in Fig. 6.

parts being broken away to better illustrate construction thereof.

Fig. 8 is a vertical section through the first course of units illustrated in Fig. 6.

Fig. 9 is a horizontal section through one end of the wall shown in Fig. 6, particularly illustrating the formation of a pilaster therein.

Fig. 10 is a detail perspective view of a pair of adjacent precast units showing a modified form of interconnecting means.

Referring more in detail to the drawings, and first to the form of the invention illustrated in Figs. 1 to 5 inclusive;

1 designates a hollow concrete wall structure, for example the side walls of a small building such as a residence or the like. In carrying out the invention, the walls may be supported on the marginal portions of the floor slab 2 which may overlap the foundation walls, or the side walls 10 may be supported directly upon the foundation walls. In either event, the supporting element is provided with spacer strips 3 which may be separately formed and suitably attached to the supporting element or be formed integrally therewith. The spacer strips 3 preferably extend continuously with the walls and are inset to provide inner and outer ledges 4 and 5 and vertical faces 6 and 7.

The walls illustrated are preferably divided into 30 bays 8 defined by batten-like members 9 representing pilasters. Each bay includes inner and outer monolithic slab-like units 10 and 11. The units may be of such size that when the edges 12 and 13 thereof are supported on the ledges 4 and 5, the upper edges 14 and 15 support a cap plate 16 on which the roof rafters 17 are supported. The ends 18 of the slabs extend perpendicularly and are overlapped, as at 19, with the batten-like members 9, or they may abut one another.

The inner and outer units may be provided with window openings 20 that extend downwardly from the upper edges 14 and which are adapted to be encased by frame units comprising side 45 jambs 21 and 22, a sill unit 23, and a header unit 24, all of which are precast and correspond in width to the thickness of the wall. The inner faces 25 of the frame units are provided with grooves 26 to accommodate the marginal edges 50 of a window frame 27. The portion of the opening 20 above the header 24 is closed by lintel units 28 and 29, the ends of which engage block sections 30 and 31 forming continuations of the jambs 21 and 22.

The window frame units just described and

cap plates 16 are preferably secured in position by means of dowels 32 which project from the edges of the inner and outer wall slab units to engage in sockets 33 provided in the faces of the respective frame units.

In the bays having door openings 34, the inner and outer wall units are divided to accommodate the door frames which are formed of precast jambs 35 and a header 36, corresponding to the window jambs and header above described. The upper portion of the door opening is closed by lintels 37 and 38 having their ends abutting against block sections 39 which form 39 which form upper continuations of the jambs 35, the header 36 being supported directly on the upper ends of the jambs so that the weight of the lintels is supported thereon. These parts are also secured together by the dowel and socket connections as previously described.

The end edges of the inner and outer slab units are provided with rods 40 and 41. The vertical batten-like members of the corner bays have their outer edges overlapped as at 42 and the corner edges of the inner slab units abut against each other as indicated at 43. The rods 40 and 41 have projecting ends which overlap and are tied together by wires 44. The batten members are secured to the projecting ends of the rods by wire ties 45 that are incorporated into the reinforcement 46 thereof. The spaces 47 between the slab units are closed at the ends by strips of metal or the like 48 which may be slid into position between the projecting ends of the rods 40 and 41 so as to cooperate with the overlapping corner battens in forming a hollow corner column which may be filled with concrete as indicated at 49 to form a solid column. Adjoining bays in the same side wall are spaced apart preferably at a partition 50 and the spaces between the outer slabs are bridged by one of the batten strips. The partition may be formed of spaced slabs 51 similarly to the side walls with the outer edge corners thereof abutting the corresponding edge corners of the inner slabs of the side wall. The spaces between the slabs are also closed by plates 48 to form a column 52 which is filled with concrete 53.

The lower margins of the slab units 10 and 11 are provided at a point above the spacer strips 3 with bushings 54 and 55 to pass drawbolts 56. In order that the heads 57 and nuts 58 on the bolts may be countersunk from the outer surfaces of the slabs, the slabs have recesses 59 registering with the bushings 54 and 55. The upper portions of the slab sections have tie wires 60 and 61 imbedded therein and have projecting ends 62 which are twisted together as later described. Imbedded in the inner surface of one of the slab sections are threaded sockets such as nuts 63 for receiving the threaded shanks of spacing bolts 64.

The slab units forming the inner and outer portions of the respective bays may be cast at the site of construction. For example, suitable forms may be laid directly upon the floor 2, preferably with paper thereunder to prevent adhering of the concrete to the floor. The sides of the form may be provided with suitable openings through which the dowels 32 are projected. The forms may also be provided with suitable cores for forming the sockets 33. The form is then poured with concrete and the internal reinforcing, for example ordinary mesh 65, is pressed thereinto, bights of wire being looped through selected meshes to provide the ties 60 and 61. The nuts 63 of the spacing bolts 64 are then pressed into the concrete. The bushings 54 and 55 and the cores (not

shown) for making the recesses 59 are imbedded in their proper positions in the concrete prior to setting thereof. The concrete is then allowed to acquire its initial set, after which the forms are removed and the units properly cured. The jamb, sill and header units, as well as the lintel and filler block sections surrounding the door and window openings may be cast in a similar manner. The batten members may likewise be preformed on the job.

When the erection is to take place, the inner and outer slabs 10 and 11 of the respective bays are raised to position so that the lower edges 12 and 13 thereof seat upon the ledges 4 and 5 at opposite sides of the strips 3. The drawbolts 56 are then applied to clamp the lower edges of the inner and outer slabs against the spacing strips 3. The spacing bolts 64 are then adjusted so that the top edges 14 and 15 of the slabs are spaced apart in conformance to the spacing effected by the strip 3, after which the ends 62 of the ties 60 and 61 are twisted together as indicated at 66 to support the wall slabs in position. The sills 23 are then placed in position, followed by the jambs 21 and 22, which are retained in position by the dowels 32 projecting from the edges of the window openings. The window frame 27 is inserted in the grooves 26. The header section is then placed in position so that the ends are supported directly on the ends of the jamb sections, after which the block sections 30 and 31 are seated on the ends of the header section as shown in Fig. 1. The lintel sections 28 and 29 are then moved to position. The door frames are similarly assembled, after which the batten members 9 are applied so that they overlap the adjacent edges of the outer slab units of the adjacent bays and the wires 44 thereof are twisted around the ends of the rods 40 and 41 projecting from the edges of the inner and outer slab units. The plates 41 are then moved into position to close the spaces 46 and form the sides of the columns which are filled with concrete. If desired the space between the inner and outer slab units may be filled with insulation material or it may be left open to provide dead air spaces. The space between the lintels over the doors and windows can be filled with concrete as indicated at 67 to carry the load thereabove. The cap plate 16 is then applied so that the sockets 33 therein engage over the upwardly projecting dowels 32 with the side edges resting upon the upper edges 14 and 15 of the slab units.

The advantages of this type of construction are that a carpenter can lay out and make a great number of the outlining forms in a day and supervise their forming operations. The rest of the operations may be performed by common labor. The erection of the units is less expensive than the erection of wood forms. The completed wall requires no force gun grouting to make it weather-tight since there are no ties extending through to the exterior of the units or any erection holes. The completed wall provides a hollow, light weight construction that may be thoroughly insulated to provide a weather-proof wall. The units also have uniform appearance and there is no possibility of rust streaks or defects marring the exterior surfaces. The job is also cleaner and safer as no great piles of lumber reinforcing are required, nor are nails required in holding the forms together.

In the form of the invention shown in Figs. 6 to 9 inclusive, the inner and outer wall sections 67 and 68 may be formed of a plurality of flat,

slab-like units 69 laid upon edge in superimposed courses. The units are formed in the same manner as the slabs previously described, and are of substantially rectangular shape and of relatively narrow thickness to provide side edges 70—71, upper and lower edges 72—73, an outer face 74, and an inner face 75. The upper edge 72 and side edges 71 are provided with projecting dowels 76 which are inset into the concrete similar to the dowels previously described. The edge 70 is provided with sockets 77 to receive the dowels on the side edge 71 of an adjacent unit. The lower edge 73 is likewise provided with sockets 77 which are of somewhat longer dimension to engage the dowels 76 in a next lower course and to permit shifting of the units so that the sockets 77 receive the dowels 76 on an adjacent unit, as shown in Fig. 6. The units are provided with ordinary mesh reinforcement 78 to which the bights or ties 79 are connected, the ties having ends 80 and 81 projecting therefrom and which are adapted to be twisted together with the ties of the facing unit, as indicated at 82. The inner faces 75 of the outer units are preferably provided with nuts 83 of spacer bolts 84. In setting up the wall the inner and outer units are supported on the foundation 85 which has reinforcing dowels 86 projecting upwardly therefrom to key the wall thereto. The outer units are preferably the first laid up and are suitably braced (not shown) from the exterior side as in ordinary wall supporting practice. These particular units are preferably provided with openings 87 therein through which ties (not shown) are extended for securing the units to the braces so that the wall is supported in perpendicular position. After completing the outer section of the wall, the space between the units may then be provided with the necessary reinforcing. The units composing the inner section are then laid up in courses. The spacer bolts 84 are threaded into the nuts 83 and adjusted so as to space the inner section, after which the ties 80 and 81 of the inner and outer units are twisted together, as indicated at 82, to draw the inner units against the heads of the bolts. The space is then filled with concrete 88 to form a solid wall structure.

This structure is also adapted to the formation of pilasters, beams, and the like, as indicated at 89, by the use of special units 90 and 91 that are set up to form the pilasters. When the spaces between the units are filled with concrete, as at 88, a solid wall structure is provided having the pilasters or columns similar to ordinary concrete construction.

The form of the invention shown in Fig. 10 is similar to that illustrated in Figs. 6 to 9 inclusive, however, the dowels are omitted and the adjacent edges of the units are secured together by means of angles 93 having ends 94—95 projecting from the inner faces of the units at the edges thereof to be interconnected by fastening devices such as bolts 96 or by crimping the ends together. In this form of the invention, the units, with the exception of those forming the pilasters and beams, are all of the same shape and dimensions and when laid up constitute forms for the poured concrete and when the concrete is set up they become an integral part of the wall, being thoroughly attached by means of the interconnected tie wires. This particular form is adapted for attachment to existing walls or where sliding of the units is impracticable. If desired, the customary reinforcing may be inserted in the space 75

prior to pouring of the concrete, however, less reinforcement is required than in ordinary construction due to the reinforcing effects of the spacing bolts, tie wires, and mesh contained in the respective units.

From the foregoing it is obvious that I have provided a building construction composed of precast units so as to facilitate erection of concrete structures and reduce the cost thereof.

- 10 Attention is also directed to the fact that the poured concrete is not affected by heat and other weather conditions during setting thereof since it is thoroughly protected by the inner and outer wall units.
- 15 What I claim and desire to secure by Letters Patent is:
1. A building construction including a support, bays each comprising spaced inner and outer slab-like units of monolithic construction, bat-ten-like members constituting pilasters joining the ends of said bays, means adjacent the lower margin of said slabs spacing the units of one side from the units of another side, recesses in the lower margins of said slab-like units provided with bushings, bolts for passage through said recesses to clamp the units against the spacing means, means in the inner surface of one of the slab sections receiving an adjustable spacing bolt, the opposite end of which has contact engagement only with the opposite slab unit, ties connecting said units, said ties comprising wires having their ends imbedded in the walls of the respective slabs, the outer ends of the ties of one slab twisted to the ties of the opposite slab 30 to retain the units together, and a concrete core filling the space between said units said ties constituting a reinforcement for said concrete.
  2. A building construction including, bays each comprising spaced reinforced slab-like units, ties 40 consisting of wires looped through said reinforcement and embedded in the walls of said units, the free ends of said wires projecting from said units to draw the units together, columns at the ends of said bays, a threaded socket embedded adjacent the upper edge of one of said units, an adjustable spacing bolt provided with a threaded shank fitting into said threaded socket and having a head on the opposite end engaging against the side of an opposing unit, rods projecting from the ends of said units and anchored in said columns, cap plates closing the space between said units at the upper edges thereof, and insulating material filling the space between said units.
  3. A building construction including a sup- 55 port, a raised spacing strip on said support whereby an inner and outer ledge is provided thereon, a plurality of juxtaposed relatively thin slab-like units constituting opposite walls of a form, said units being seated in said ledges and held in engagement with the opposite sides of the spacing strip by means of adjustable bolts passing through the lower margins of said units whereby said walls are maintained in spaced re- 60 lation, a threaded socket embedded adjacent the upper edge of each of said units of one wall, an adjustable spacing bolt provided with a threaded shank fitting into said threaded socket and having a head on the opposite end engaging against the side of an opposing unit, and ties connect- 65 ing said opposed units, said ties comprising wires embedded in the units and having ends pro- truding therefrom, the ends of the ties of one unit twisted to the ends of the ties of the oppo- 70 site unit to retain the units together.

4. A building construction including a support, bays each comprising spaced inner and outer slab-like units of monolithic construction, bat-ten-like members constituting pilasters joining the ends of said bays, means adjacent the lower margins of said slabs spacing the units of one side from the units of another side, recesses in the lower margin of said slab-like units provided with bushings, a bolt for passing through said recesses clamping the units against the spacing means, a threaded socket embedded in the top edge of one of said units, an adjustable spacing bolt provided with a threaded shank fitting into said threaded socket and having a head on the opposite end engaging against the side of an opposing unit, and ties connecting said units, said ties comprising wires having their ends imbedded in the walls of the respective slabs, the outer ends of the ties of one slab twisted to the ties of the opposite slab to retain the units together.

5. A building construction including a support, a raised spacing strip on said support whereby an inner and outer ledge is provided thereon, a plurality of juxtaposed relatively thin slab-like units constituting opposite walls of a form, said units being seated in said ledges and held in engagement with the opposite sides of the spacing strip by means of adjustable bolts passing through the lower margins of said units whereby said walls are maintained in spaced relation, a threaded socket embedded adjacent the upper edge of each of said units of one wall, an adjustable spacing bolt provided with a threaded shank fitting into said threaded socket and having a head on the opposite end engaging against the side of an opposing unit, ties connecting said opposed units, said ties comprising wires em- bedded in the units and having ends protruding therefrom, the ends of the ties of one unit twisted to the ends of the ties of the opposite unit to retain the units together, dowels in selected edges of said units, and elongated sockets in the opposite edges of said units for receiving the cor-

responding dowels of an adjacent unit when a unit is assembled in a wall.

6. A building construction including a support, a raised spacing strip on said support whereby an inner and outer ledge is provided thereon, a plurality of juxtaposed relatively thin slab-like units constituting opposite walls of a form, said units being seated in said ledges and held in engagement with the opposite sides of the spacing strip by means of adjustable bolts passing through the lower margins of said units whereby said walls are maintained in spaced relation, a threaded socket embedded adjacent the upper edge of each of said units of one wall, an adjustable spacing bolt provided with a threaded shank fitting into said threaded socket and having a head on the opposite end engaging against the side of an opposing unit, means anchored in the respective units terminating short of the out-side of said units providing an unbroken finish on the outside surface of said units, and means for connecting said anchoring means to retain said units together.

7. A building construction including a support, bays each comprising spaced inner and outer slab-like units of monolithic construction, means adjacent the lower margins of said slabs spacing the units of one side from the units of another side, recesses in the lower margin of said slab-like units provided with bushings, a bolt for passing through said recesses clamping the units against the spacing means, a threaded socket embedded in the top edge of one of said units, an adjustable spacing bolt provided with a threaded shank fitting into said threaded socket and having a head on the opposite end engaging against the side of an opposing unit, and ties connecting said units, said ties comprising wires having their ends embedded in the walls of the respective slabs, the outer ends of the ties of one slab twisted to the ties of the opposite slab to retain the units together.

RALPH D. YANKEE.
